FIG. 1

FIG. 2

FIG. 3

FIG. 4

FIG. 1 is a top plan view of a toy horse showing my new design.

FIG. 2 is a side elevational view.

FIG. 3 is a front elevational view.

FIG. 4 is a rear elevational view.

The side not shown has substantially the same appearance as the side shown in FIG. 2. The dominant features of the design reside in the portion shown in the drawing in full lines.

I claim:

The ornamental design for a toy horse, as shown and described.
